UNITED STATES PATENT OFFICE.

CHARLES WILLIAMS HAWKES, OF ALLENTOWN, PENNSYLVANIA.

WATER-JACKET.

No. 921,542.

Specification of Letters Patent.

Patented May 11, 1909.

Application filed January 11, 1909. Serial No. 471,655.

To all whom it may concern:

Be it known that I, CHARLES WILLIAMS HAWKES, citizen of the United States, residing at Allentown, in the county of Lehigh 5 and State of Pennsylvania, have invented a certain new and useful Improvement in Water-Jackets, of which the following is a full, clear, and exact description, reference being had to the accompanying drawings, 10 forming a part hereof.

My invention has relation to improvements in water-jackets for cupola, blast and similar furnaces; and it consists in the novel construction of jacket more fully set forth in the 15 specification and pointed out in the claims.

In the drawings Figure 1 is a longitudinal section on the line 1—1 of Fig. 2 showing one form of my invention; Fig. 2 is an elevation of one-half of the jacket broken above the 20 twyers; Fig. 3 is a sectional detail of the stay-bolt connection between the sheets; Fig. 4 is a sectional detail showing a modified form of stay-bolt connection; and Figs. 5 and 6 are similar sectional details showing still other 25 modifications of construction.

The present invention is an improvement on the construction of water-jacket shown and described in U. S. Letters Patent 815,013 issued to me under date of March 13, 30 1906, and while having the same objects and purposes as the patented construction, it is susceptible of a number of modifications any one of which may fulfil the requirements of what shall constitute a good, commercial, 35 durable and useful water-jacket.

The improvement herein is directed to the connection between the sheets or walls of the water-jacket and the stay-bolts, which latter, though not directly welded to either sheet, 40 yet are so united thereto that all danger of leakage is eliminated.

The advantages of the invention will be better apparent from a detailed description thereof which as is as follows:

Referring to the drawings, and for the present to Figs. 1 to 3 inclusive, 1, represents the inside sheet or fire-sheet, and 2, the outside sheet of the water-jacket. In the present improvement (as in the patented construction referred to) any and all rivet-heads are eliminated from the inside sheet, this being accomplished by one of several methods. In the figures referred to, (1, 2, 3) a hole is reamed in the inside sheet (the hole being 50 preferably one which tapers inward) and through this hole is inserted the stay-bolt 3,

the opposite end of the bolt terminating in a reduced stem 4 which is passed through an opening in the outside sheet and subsequently riveted on the outside to said outside sheet, (as in my patent aforesaid). The end of the bolt engaging the opening in the inside sheet 1, is flared to conform to the taper of the hole, but does not fill the hole completely. Into the portion of the hole 55 thus left unfilled by the bolt is subsequently inserted a plug 5 which is welded to the inside sheet, the plug thus becoming virtually an integral part of the sheet and flush with the outer face thereof, that is to say the face 60 which is exposed to the heat of the furnace and to the ore charge. The bolt thus has one end embedded as it were in a socket formed for its reception in the inside sheet, such socket being formed by the hole originally reamed in the sheet and subsequently closed at its outer end by the plug 5 welded to the sheet, and since the weld forms a seamless joint, it is evident that leakage at such 65 joint is impossible.

In Fig. 4 the hole in the inside sheet is formed by punching and drifting thus leaving a tapering hollow nipple *n* projecting into the jacket, the bolt 3' being flared to conform to the taper of the nipple. Like in the form 70 first described, the plug 5 is inserted into the cavity opposite the end of the bolt and welded to the sheet. The bolt is secured to the outside sheet in the same manner as that 75 described in connection with Figs. 1, 2, and 3.

In Fig. 5, I show an ordinary screw stay-bolt 3''. In this case the stay-bolt is screwed into the inside sheet, but does not pass all the way through. That portion of the threaded hole formed in the sheet and left unoccupied 80 by the bolt, is filled by the plug 5 which is welded to the sheet. The outside sheet end of the bolt can of course be secured to its sheet as shown in Fig. 5, that is by shouldering the same to the sheet, and riveting the 85 bolt on the outside to the sheet; or, as shown in Fig. 6, the bolt 3''' could be screwed to both sheets, and riveted to the outside sheet. In fact so far as the outside sheet is concerned, any of the usual constructions could 90 be followed with any of the bolts here proposed.

It will be seen that so far as shouldering the bolt to the sheets is concerned, this shouldering is limited to one of the sheets only, 95 namely the outside sheet. This permits the two sheets to be first riveted together at their

- flanges; the drilling and the countersinking, or the drilling and the drifting, or the drilling and the screw-threading, can be done after the sheets have been riveted together; 5 then the bolt is passed or placed through the two sheets from the inside sheet (as is obvious). In the event the bolt should be screwed into the inside sheet (sometimes called the inner sheet) and shouldered against 10 the outside (outer) sheet, a groove *s* is made in the bolt for screwing the same to a tight bearing between the outer sheet and the shoulder, by means of a screw driver. Of course, in order that a bolt may be passed 15 through the sheets in the manner outlined above, after the sheets have been riveted together at the flanges, the opening in the sheet into which the bolt is first inserted (the inside sheet) must necessarily be equal to or 20 larger than the opening in the opposite sheet (outside sheet). This is obvious from an inspection of the drawings.

It is not to be inferred from the foregoing that the constructions described and claimed 25 are to be limited in their application to water-jackets specifically. The invention may be applied to air jackets, boilers, and all other constructions where stay-bolts are employed. It is possible of course, that in the welding of 30 the plug 5 to the inside sheet, it (the plug) may incidentally adhere to the end of the bolt which it protects and covers, but the welding of the plug to the bolt is not herein contemplated. The bolts may be so inserted 35 as not to necessarily make a right angle with the sheets, a slight inclination of the bolt constituting no departure from the present invention. In fact, in boiler constructions, stays, and stay-bolts do assume almost any 40 conceivable angle with the sheets to which they are secured.

In the drawings the weld is shown by a distinct hatching, though in practice the plug will be so merged with the body of the sheet 45 as to leave no distinct line or seam of demarcation, and will practically become an integral part of the sheet.

Having described my invention what I claim is:

- 50 1. A jacket comprising an inside and an outside sheet, the inside sheet being provided with openings having their outer ends closed by plugs welded to the sheet and thereby forming sockets, stay-bolts having one end 55 embedded in said socket and the opposite end engaging the outside sheet.

2. A jacket comprising an inside and an outside sheet, the sheets being provided with oppositely disposed openings, stay-bolts inserted 60 into the openings and terminating at points between the ends of the openings formed in the inside sheet, plugs inserted

into the portions of the openings in the inside sheet left unfilled by the bolts, and welded to the inside sheet, the opposite ends of the 65 bolts being secured to the outside sheet.

3. A jacket comprising an inside and an outside sheet, the sheets being provided with oppositely disposed openings, stay-bolts inserted into the openings and terminating at 70 points between the ends of the openings formed in the inside sheet, plugs inserted into the portions of the openings in the inside sheet left unfilled by the bolts, and welded to the inside sheet, the opposite ends of the bolts 75 being shouldered against the outside sheet and riveted thereto on the outside thereof.

4. A jacket comprising an inside and an outside sheet, the inside sheet being provided with an opening terminating in the planes of 80 the opposite faces of the sheet, the outside sheet having an opening opposite thereto, a stay-bolt having its end inserted in said openings and terminating in the opening of the inside sheet at a point between the opposite 85 faces of the sheet, and a plug inserted into the unfilled portion of the opening in the inside sheet and welded to the sheet, the opposite end of the stay-bolt being secured to the outside sheet. 90

5. A jacket comprising an inside and an outside sheet, the inside sheet being provided with an inwardly tapering opening terminating in the planes of the opposite faces of the sheet, the outside sheet having an opening 95 opposite thereto, a stay-bolt having its ends inserted in said openings and terminating in the opening of the inside sheet at a point between the opposite faces of the sheet, and a plug inserted into the unfilled portion of the 100 opening in the inside sheet and welded to the sheet, the opposite end of the stay-bolt being secured to the outside sheet.

6. A jacket comprising an inside and an outside sheet, the inside sheet having sockets 105 formed therein provided with closed bottoms, and stay-bolts having one end resting in the sockets and the opposite end secured to the outside sheet.

7. A jacket comprising an inside and an outside sheet, the inside sheet having openings formed therein, plugs welded to the inside sheet and closing the outer ends of the openings aforesaid, thereby forming suitable sockets, and bolts projecting out of said sockets across the space between the sheets and secured with their opposite ends to the outside sheet. 115

In testimony whereof I affix my signature, in presence of two witnesses.

CHARLES WILLIAMS HAWKES.
